UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMINGTON, PENNSYLVANIA, A CORPORATION OF PENNSYLVANIA.

FLUID-PRESSURE BRAKE.

Application filed October 7, 1926. Serial No. 140,084.

This invention relates to fluid pressure brakes, and more particularly to means for retaining fluid under pressure in the brake cylinder, in the operation of releasing the 5 brakes.

In the running of railway trains, when descending grades, it is desirable to retain fluid pressure in the brake cylinder when the 10 brake pipe pressure is increased to release the brakes, so that the auxiliary reservoirs throughout the train may be recharged from the brake pipe, without releasing the brakes.

The principal object of my invention is to provide means, under the control of the 15 engineer, whereby the brake cylinder pressure retaining means may be cut in when the train is descending a grade and cut out when the train is running on a level.

In the accompanying drawing, the single 20 figure is a view of a fluid pressure brake equipment, showing my invention applied thereto.

As shown in the drawing, the brake equipment may comprise a triple valve device 1, 25 connected to the usual brake pipe 2, an auxiliary reservoir 3, and a valve device 4 comprising a casing containing a flexible diaphragm 5.

The chamber 6, at one side of said diaphragm, is connected by a pipe 7 to the auxiliary reservoir 3 and chamber 8, at the opposite side of the diaphragm, contains a coil spring 9 which acts on a diaphragm follower 10 engaging the diaphragm. A valve 35 11 is contained in valve chamber 12 and is provided with a stem 13, adapted to be engaged by a stem 14 carried by the diaphragm follower 10.

The chamber 12 is connected by a pipe 15 40 to the usual exhaust port of the triple valve device 1 and said chamber is also connected through a restricted port 16, with a valve chamber 17, containing a valve 18, adapted to control communication from valve chamber 17 to the atmosphere.

The valve 18 is operable by a flexible diaphragm 19, having a diaphragm follower 20 engaging the diaphragm at one side and said follower having a stem 21, adapted to engage the stem of valve 18. The chamber 22, at one side of the diaphragm 19, is connected by a passage 23 to diaphragm chamber 6 and is therefore subject to fluid at auxiliary reservoir pressure. A coil

spring 24 is mounted in chamber 25, at the 55 opposite side of the diaphragm 19 and acts on the follower 20.

In operation, a higher standard brake pipe pressure is carried when operating on level roads than is carried when the train 60 is operating on a grade, such as 90 pounds in level road service and 70 pounds in grade service.

The spring 9 is such that an auxiliary reservoir pressure, slightly in excess of 70 65 pounds, is required to operate the diaphragm 5, so as to open the valve 11 and when operating in level road service with a normal standard brake pipe pressure of 90 pounds, the diaphragm 5 will be operated to hold 70 the valve 11 open and said valve will be held open in applying the brakes, even if the auxiliary reservoir pressure be reduced substantially to the equalizing point, 70 pounds. 75

With the valve 11 open, the brake cylinder exhaust port of the triple valve device 1 is connected through pipe 15 and past the open valve 11 to an atmospheric exhaust port 26, and consequently, the brakes will be released in the usual manner in releasing the 80 brakes, without retaining fluid under pressure in the brake cylinder.

In operating on a grade, a lower standard brake pipe pressure of 70 pounds is carried 85 and at this pressure, the diaphragm 5 permits the valve 11 to close, so that the atmospheric exhaust port 26 is cut off from the brake cylinder exhaust pipe 15 and fluid from the brake cylinder can only exhaust 90 through the restricted port 16.

The spring 24, acting on the diaphragm 19, is such that the auxiliary reservoir pressure in chamber 22 will be effective on diaphragm 19 to hold the valve 18 open, unless the auxiliary reservoir pressure is reduced to a very low degree, say less than 50 pounds, which pressure is the equalizing point when the standard brake pipe pressure carried is 70 pounds. The valve 18 is therefore normally held open and in releasing the brakes in grade service, fluid will only escape from the brake cylinder at a rate corresponding with the size of the restricted port 16. As a consequence, fluid under pressure is 105 retained in the brake cylinder for a sufficient time to permit the auxiliary reservoir to be recharged.

If the auxiliary reservoir pressure should fall below the pressure at which the spring 24 is adjusted, the diaphragm 19 will be operated to permit the valve 18 to seat. The 5 fluid pressure, then in the brake cylinder, is thus retained and will not escape until the auxiliary reservoir pressure has been increased sufficiently to cause the diaphragm 19 to be operated so as to again open the valve 10 18.

In order to be able to cut the brake cylinder pressure retaining feature out of action, a cock 27 may be provided, having an operating handle 28. When it is desired to cut 15 the retaining valve device out of action, the handle 28 is operated to turn the valve 27, so that port 29 connects chamber 12 with an atmospheric exhaust port 30. The brake cylinder exhaust pipe 15 is then connected 20 directly to the atmosphere, so that the triple valve device will operate in the usual manner to exhaust fluid from the brake cylinder to the atmosphere, when the brake pipe pressure is increased to effect the release of the 25 brakes.

Having now described my invention, what I claim as new and desire to secure by Letters Patent, is:—

1. In a fluid pressure brake, the combination 30 with a triple valve device, a brake pipe, and an auxiliary reservoir, of means for controlling the brake cylinder triple valve exhaust port and operated by auxiliary reservoir pressure to connect said exhaust port to an unrestricted atmospheric port when a high brake pipe pressure is carried and to maintain said connection until the auxiliary reservoir pressure is reduced substantially to the degree at which the brake pipe pressure 35 equalizes with the auxiliary reservoir pressure.

2. In a fluid pressure brake, the combination 40 with a triple valve device having the usual brake cylinder exhaust port, a brake pipe and auxiliary reservoir, of means having a chamber connected to said brake cylinder exhaust port, a valve for controlling communication from said chamber to an

unrestricted exhaust port, and a movable abutment subject to the opposing pressures 50 of the auxiliary reservoir and a spring for operating said valve.

3. In a fluid pressure brake, the combination with a triple valve device having the usual brake cylinder exhaust port, a brake 55 pipe and auxiliary reservoir, of means having a chamber connected to said brake cylinder exhaust port, a valve for controlling communication from said chamber to an unrestricted exhaust port, and a movable abutment subject to the opposing pressures of the auxiliary reservoir and a spring for operating said valve, said chamber having a restricted exhaust port for venting fluid from said chamber at a restricted rate. 65

4. In a fluid pressure brake, the combination with an auxiliary reservoir and a triple valve device having the usual brake cylinder exhaust port, of a valve device for controlling the exhaust of fluid through said exhaust port and having a chamber with two exhaust ports, one of which is restricted, a valve for controlling the other exhaust port, and a movable abutment subject to the opposing pressures of the auxiliary reservoir 70 and a spring for operating said valve. 75

5. In a fluid pressure brake, the combination with an auxiliary reservoir and a triple valve device having the usual brake cylinder exhaust port, of a valve device for controlling the exhaust of fluid through said exhaust port and having a chamber with two exhaust ports, one of which is restricted, a valve for controlling the other exhaust port, a movable abutment subject to the opposing pressures of the auxiliary reservoir and a spring for operating said valve, a second 80 valve for controlling communication through said restricted exhaust to the atmosphere, and a movable abutment subject to the opposing pressures of the auxiliary reservoir and a spring for operating said valve. 85 90

In testimony whereof I have hereunto set my hand.

CLYDE C. FARMER.
